UNITED STATES PATENT OFFICE.

FRANK E. THOMES, OF PORTLAND, MAINE.

CORE-BOX CUTTER.

No. 824,962.

Specification of Letters Patent.

Patented July 3, 1906.

Application filed June 7, 1905. Serial No. 264,055.

To all whom it may concern:

Be it known that I, FRANK E. THOMES, a citizen of the United States of America, and a resident of Portland, county of Cumberland, State of Maine, have invented certain new and useful Improvements in Core-Box Cutters, of which the following is a specification.

My invention relates to a core-box cutter, and particularly to certain improvements in my machine as patented February 23, 1904, No. 753,178.

In the above-mentioned machine a gear was secured to the end of a horizontal shaft, said gear engaging a second gear which was above it and which was pivoted on a stud projecting out from a bracket extending upward from the journal-box of the main shaft. Secured to the upper gear was a cutter-head which worked up through a slot in the table of the machine.

My present invention relates, first, to providing a bearing on each side of the cutter-head instead of pivoting it on a stud, as shown; second, in making the cutter-head, the two gears, and their connecting mechanism quickly and easily removable as a whole, whereby they may be easily shifted and, finally, in providing an adjustable pivoting-point adapted to pivot the block on a center over the cutter-head, whereby a hemispherical or annular recess may be formed in the block. These features of construction I will now proceed to specifically describe.

My invention is illustrated by means of the accompanying drawings, which show a core-cutting machine provided with my improvements.

In the drawings, Figure 1 is a vertical section parallel with the shaft, showing the working parts in elevation. Fig. 2 is a section on the line $x-x$ of Fig. 1. Fig. 3 is an enlarged longitudinal section through the cutter-head and connecting mechanism with portions in elevation. Figs. 4 and 5 are plan views of blocks, showing the form of channels cut by the use of my pivoting device. Fig. 6 is a section on the line $x-x$ of Fig. 3, and Fig. 7 is a plan view.

Referring to Figs. 1 and 2, A represents the table; a , the standard which supports the table; a' , the horizontal slot through which the cutter-head works; b^2 , the main shaft; b , and b' the journal-boxes of the main shaft, and g the main gear. k is the screw by which the

table is raised and lowered, and k' is a hand-wheel for operating the same. These parts are all substantially as shown in my prior patent and need no further explanation. Means are provided by which the cutter-head arbor, when a small cutter is to be used, may be supported on both sides of the cutter-head. For this purpose I form a bracket c , Fig. 3, which comes up outside of and above the upper level of the main gear, and in the upper end of this bracket is journaled the outer end of the arbor e' , on which is secured the cutter-head f and adjacent thereto the pinion e . As here shown, the other end of the arbor e' is pivoted on a conical stud d , which projects outward from the upper portion of the box in which the outer end of the shaft is journaled. t represents the cutter held in a transverse hole in the cutter-head by a set-screw f' .

For the purpose of making the cutting mechanism readily removable for the purpose of changing cutters I provide an extension-box C , in which is journaled a short sleeve g^2 , on the outer end of which the gear g is secured. The sleeve g^2 is adapted to slip on over the end of the shaft, and clutch mechanism is provided to hold it in place on the shaft.

As here shown, projections b^3 are formed on the shaft, and slots or recesses are formed in the inner end of the sleeve, which recesses interlock or engage the projections b^3 in the well-known manner. To hold the sleeve in place, a nut g' is screwed on its inner end over the recesses, this nut being contained in a recess in the extension-box C . The extension-box is held in place by means of a rearward extension c' , which fits on top of the journal-box b' and is secured in place by a screw c^2 . I have represented in Fig. 2 the cross-section of a block in process of being channeled, and in connection with such channels I may form annular or hemispherical recesses. For this purpose means are provided for pivoting the block o at a point on top and over the cutter-head. For this purpose I provide a horizontal adjustable arm i , held in a socket i^2 , secured to the clamp h , provided with a clamping-nut h' . The end of the arm i is turned downward, and a pin i^3 extends down through, forming a pivoting-point adapted to enter the top of the block. In practice a small hole is bored to admit the pin. The pin i^3 may be located directly over the center of the cutter-head when a hemispherical re-

cess is to be formed, or it may be located away from the head when a U-shaped channel is to be cut, as shown in Fig. 4.

In Fig. 4 I show the under side of a block 5 in which has been cut a U-shaped recess by the use of my improved machine. In this operation the block is run over the cutter, forming the half-round channels r in the usual way, to the dotted line $p^2 p^2$, a hole having 10 been formed in the upper surface of the block opposite the point p . Into this hole the pin i^3 is introduced and the arm i clamped in place. The block O is now swung around one hundred and eighty degrees and is then 15 run straight, forming the other channel r' , parallel with the channel r . When a channel is to be terminated, as shown in Fig. 5, by a spherical end, the cutter is run straight to the point p' in the center of the channel, and 20 the pin i^3 is inserted in the top of the block opposite this point. The block is then swung around one hundred and eighty degrees, as before, and the special end thus cut.

The operation of my machine and the use 25 of the above-described improvements will be readily understood. The cutter-head projects up through a slot in the table and is provided with mechanism here shown, by which it may be raised and lowered vertically. The 30 block to be cut is run over the cutter-head parallel with its axis, cutting first a shallow channel, which is gradually deepened by raising the cutter-head until the channel becomes semicylindrical in form. When small 35 cutter-heads are to be used, the outside bracket c furnishes a support for the outer end of the arbor, and there is sufficient space between the body of the bracket and the gear to allow the cutter to revolve.

40 By constructing the cutter-head and gears, as shown, mounted in the extension-box the whole can be quickly changed to substitute one cutter for another. The pivoting-arm enables me to cut either hemispherical or annular channels quickly and easily.

I claim—

1. In a core-box cutter, the combination of a journal-box, a main shaft journaled therein, a gear on the end of said shaft, a 50 bracket on the end of said box extending above and outside of said gear, an arbor one end of which is journaled in the upper portion of said bracket and one end in the upper portion of said box, a pinion on said arbor engaging said gear, a cutter-head adjacent to said pinion, a cutter in said cutter-head being

adapted to rotate in the space between said bracket and said gear.

2. In a core-box cutter, the combination of a journal-box, a main shaft journaled 60 therein, a gear on the end of said shaft, a bracket on the end of said box extending above and outside of said gear, an arbor, one end of which is journaled in the upper portion of said bracket, a stud on said box on which 65 the other end of said arbor is pivoted, a pinion on said arbor engaging said gear, a cutter-head adjacent to said pinion and a cutter in said cutter-head adapted to rotate in the space between said bracket and gear.

3. In a core-box cutter, the combination of a journal-box proper, a shaft journaled therein, an extension-box having a rearward projection adapted to be secured to said box, a sleeve journaled in said extension and 70 adapted to receive the end of said shaft, a clutch mechanism for locking the sleeve to the shaft, a gear on the outer end of said sleeve, a pinion pivoted above said gear and engaging with it and a cutter-head secured to 75 the journal of said pinion.

4. In a core-box cutter the combination of a journal-box, proper, a shaft journaled therein, an extension-box having a rearward projection adapted to be secured to said box, a 80 sleeve journaled in said extension-box and adapted to receive the end of said shaft, projections being formed on said shaft and notches in the rear end of said sleeve to engage said projections to form a clutch connection, a nut adapted to screw on the rear end of said sleeve over said notches, a gear on the outer end of said sleeve, a pinion engaging said gear and a cutter-head connected 85 with said pinion.

5. In a core-box cutter the combination of a main shaft, a gear on the end of said shaft, a pinion above said gear and engaging therewith, a cutter-head connected with said pinion, and a horizontally-adjustable arm having a downward projecting end provided with a pivoting-point adapted to enter the wood block and to form a center over the said cutter-head to form a hemispherical or annular or other like recess.

Signed at Portland, Maine, this 15th day of May, 1905.

FRANK E. THOMES.
